UNITED STATES PATENT OFFICE.

HAKON G. LINDQUIST, OF MINNEAPOLIS, MINNESOTA.

FLYING MACHINE.

Application filed July 13, 1922. Serial No. 574,604.

To all whom it may concern:

Be it known that HAKON G. LINDQUIST, a citizen of the United States of America, residing at Minneapolis, in the county of 5 Hennepin and State of Minnesota, has invented new and useful Improvements in Flying Machines, of which the following is a specification.

The object of the invention is to provide 10 a flying machine of the aeroplane type wherein the ascension and sustaining quality is due to a movement of the planes or blades serving as planes independently of the body of the structure as distinguished 15 from the forward movement of the planes with the body as in the present practice, to the end that a substantially vertical ascension may be made and the hovering of the machine in a fixed position without air 20 movement may be accomplished; and to this end the invention consists in a construction and combination of parts of which a preferred embodiment is shown in the accompanying drawings, wherein:—

25 Figure 1 is a plan view, and

Figure 2 is a front view of a flying machine constructed in accordance with the invention.

Figures 3, 4 and 5 are side views of the 30 same with the planes or blades in progressively different positions with relation to the body.

Figure 6 is a transverse sectional view enlarged taken in the plane of one of the blade 35 carrying shafts.

Figures 7, 8 and 9 are detail side views of one of the blade shaft carriers and the related parts, the latter being shown in engagement with the reversing terminal of 40 the guide rod.

Figures 10, 11 and 12 are views in different positions of the blade reversing means.

Figure 13 is a view of the means for adjusting the inclinations of the blades or 45 planes.

Figure 14 is a view of the manually actuatable controlling device whereby the rock shaft of the blade deflecting means is adjusted.

50 A conventional type of body or fuselage

20 is illustrated in the drawing, the same having conventional forms of rudder 21 and elevator 22 which may be controlled and actuated by any suitable means forming no part of the present invention.

55 The planes, blades or wings 23 which obviously may be of any preferred extent or area adapted to the purpose in view and the load to be carried are arranged in pairs at opposite sides of the body or fuselage, the several pairs of which two are shown in the 60 illustrated embodiment of the invention being arranged in different horizontal planes for movement forwardly and rearwardly in paths disposed longitudinally of the structure and respectively in different horizontal planes with the blades or planes of each pair carried by a transverse blade shaft 24 mounted in bearings on travellers 25 which traverse the upper and lower parallel 65 guides 26.

70 In connection with each blade shaft there is employed a carrier 27 having a rocker 28 which is fulcrumed concentric with the blade shaft and carries a plurality of alternately operable rack gears 29 which are in mesh and which are adapted for alternate engagement with a rack 30 which extends longitudinally of the car. One of the rack 75 gears carries a gear 31 in mesh with which is a countergear 32 also mounted upon the carrier in concentric relation with the blade shaft and provided with a bevel gear face 33 meshing with a bevel gear face 34 on a drive gear 35 which is axially disposed at 80

right angles to the countergear and is mounted on the carrier with its teeth in operative engagement with a pinion shaft 36 extending longitudinally of the car and of a length corresponding with the path of movement of the carrier. This pinion shaft is 85

motor-driven and serves to communicate rotary motion to the drive gear 35 which in turn communicates motion through the countergear to the rack gears of which one 90 or the other may be brought into engaging relation with the rack, and which, being geared to rotate in opposite directions are adapted to propel the carrier in opposite directions or respectively toward opposite 95 100

ends of the car. The rocker is provided with a trolley arm 37 provided with a terminal trolley wheel 38 which traverses a guide rod 39 also extending parallel with the path of movement of the carrier and provided at opposite ends with stops consisting in the present construction of hooks 40 for engagement with the trolley wheel at the ends of its movement in opposite directions, with the result that the rocker is thereby reversed in position and the other rack gear is brought into operative relation with the rack to reverse the direction of movement of the carrier and hence of the blade shaft with which the same is connected. The stop carrying terminal of the trolley rod 39 consists of a yielding section 39^a pivoted at 39^b to adapt it to yield as the trolley arm swings from one position to the other in the reversal of the rocker.

The carrier in addition to the gear as above noted is provided with idle retaining gears 41 and 42 which engage the pinion shaft and serve to steady the structure and maintain the drive gear in proper relation therewith.

Connected with the blade shaft 24 at any convenient point is a means for turning the same to reverse the direction of inclination 30 of the blades or wings and which in the construction illustrated consists of a toggle lever having arms 43 and 44 respectively attached to the blade shaft and a follower 45 mounted in a tubular guide 46 and exposed to the pressure of a spring 47, said guide 46 being supported from a shaft sleeve or casing 48 which is extended transversely of the car and serves as a housing for the blade shaft. The arms of the toggle 40 lever are pivotally connected at 49 and carry buffers 50, preferably spring cushioned as shown at 51 and adapted to come into contact alternately with stops 52 located at the ends of the paths of movement 45 of the blades to throw the lever from the position indicated in Figure 11 to the position indicated in Figure 12,—the neutral or intermediate position of the toggle lever being indicated in Figure 10 and the direction 50 of movement being indicated in Figure 11.

In order that the extent or angular degree of deflection of the blade or wings may be controlled there is employed a limiting follower or piston 53, also mounted in the 55 guide 46 in the path of movement of the follower 45 impelled by said spring 47 so as to act as a stop to limit the movement of the follower and hence the bowing of the toggle lever and consequently the angular 60 adjustment of the blade carrying shaft. This limiting follower or piston is provided with an ear 54 upon which is mounted a pinion 55 operating on a rack 56, and through the pinion extends an angular or as 65 illustrated a three-webbed spindle 57 ex-

tending longitudinally of and throughout the path of the blades or wings so that by the turning of the spindle and hence the movement of the pinion on the rack it is possible to vary the position of the limiting follower or piston to secure any desired freedom of movement of the follower 45 and consequently any desired angular adjustment of the blade shaft. In the construction illustrated the adjustment of the 70 spindle 57 is secured by means of a hand operated controlling lever 58 having a locking dog 59 for engagement with a suitable segment 60 and provided with a segmental 75 rack 61 engaging a pinion 62 which is secured to the end of the spindle.

Thus, the deflection, angularly, of the planes or blades may be varied proportionately and simultaneously by a single operation of the hand lever 58, to vary the positions of the stops which limit the reversing movements of the blades, and the reversal of the latter at the ends of the path of movement results in a change in the direction of inclination while maintaining a constant angular deflection from the plane of said path.

The rotation of the drive shaft 36 being constant and in one direction the reversal in the direction of movement of the blades is due to the opposite tilting of the rocker which occurs at the ends of the paths of movement of the blades, and being incidental to the movement of the carriers which accompany the blades is positive and has a constant relation to the path of movement regardless of the rate thereof.

Having described the invention, what is claimed as new and useful is:

1. An air craft having pairs of laterally extended planes or blades mounted for reciprocatory movement in parallel paths longitudinally of the line of flight, and in angularly inclined relation to their paths of movement, means for moving the pairs of planes or blades simultaneously in opposite directions between the limits of their paths of movement and means for reversing the direction of inclination of the planes or blades at the ends of their paths of movement in combination with means for simultaneously adjusting the degree of inclination of the planes or blades.

2. An air craft having pairs of laterally extended planes or blades mounted for reciprocatory movement in parallel paths longitudinally of the line of flight, and in angularly inclined relation to their paths of movement, means for moving the pairs of planes or blades simultaneously in opposite directions between the limits of their paths of movement and means for reversing the direction of inclination of the planes or blades at the ends of their paths of movement, the means for moving the pairs

- of planes or blades including a rocker mounted in co-axial relation with the planes or blades and carrying oppositely rotating rack gears, a rack arranged parallel with the path of movement of the planes or blades for alternate engagement by said gears, and means for communicating simultaneous rotary motion in opposite direction to said gears.
3. An aircraft having pairs of laterally extended planes or blades mounted for reciprocatory movement in parallel paths longitudinally of the line of flight, and in angularly inclined relation to their paths of movement, means for moving the pairs of planes or blades simultaneously in opposite directions between the limits of their paths of movement and means for reversing the direction of inclination of the planes or blades at the ends of their paths of movement, the means for moving the pairs of planes or blades including a rocker mounted in co-axial relation with the planes or blades and carrying oppositely rotating rack gears, a rack arranged parallel with the path of movement of the planes or blades for alternate engagement by said gears, and means for communicating simultaneous rotary motion in opposite direction to said gears, and consisting of a motor driven pinion shaft extending parallel with the path of the planes or blades, a drive gear mounted upon the carrier and in peripheral mesh with the pinion shaft, and a countergear for communicating motion from the drive gear to the rack gears.
4. An aircraft having pairs of laterally extended planes or blades mounted for reciprocatory movement in parallel paths longitudinally of the line of flight, and in angularly inclined relation to their paths of movement, means for moving the pairs of planes or blades simultaneously in opposite directions between the limits of their paths of movement and means for reversing the direction of inclination of the planes or blades at the ends of their paths of movement, each plane or blade having a rocking shaft, a rocker mounted in co-axial relation with said shaft and having motor driven intermeshing rack gears for alternate engagement with a rack, a trolley arm carried by the rocker, a trolley rod traversed by a terminal roller of the trolley arm, and terminal stops on the trolley rod for reversing the position of the rocker.
5. An aircraft having pairs of laterally extended planes or blades mounted for reciprocatory movement in parallel paths longitudinally of the line of flight, and in angularly inclined relation to their paths of movement, means for moving the pairs of planes or blades simultaneously in opposite directions between the limits of their paths of movement and means for reversing the direction of inclination of the planes or blades at the ends of their paths of movement, each plane or blade having a rocking shaft, a toggle having connected arms of which one is carried by said shaft and the other is provided with a yieldingly actuated follower, a stop for limiting the movement of said follower, and stops arranged in the path of the toggle at the limits of the path of movement of the plane or blade for reversing the position of said toggle.
6. An aircraft having pairs of laterally extended planes or blades mounted for reciprocatory movement in parallel paths longitudinally of the line of flight, and in angularly inclined relation to their paths of movement, means for moving the pairs of planes or blades simultaneously in opposite directions between the limits of their paths of movement and means for reversing the direction of inclination of the planes or blades at the ends of their paths of movement, each plane or blade having a rocking shaft, a toggle having connected arms of which one is carried by said shaft and the other is provided with a yieldingly actuated follower, a stop for limiting the movement of said follower, and stops arranged in the path of the toggle at the limits of the path of movement of the plane or blade for reversing the position of said toggle, means being provided for adjusting the position of the first-named stop to determine the angular deflection of the plane or blade.
7. An aircraft having pairs of laterally extended planes or blades mounted for reciprocatory movement in parallel paths longitudinally of the line of flight, and in angularly inclined relation to their paths of movement, means for moving the pairs of planes or blades in opposite directions between the limits of their paths of movement, and means for reversing the direction of inclination of the planes or blades, each plane or blade having a rocking shaft, a rocker mounted in co-axial relation with said shaft and having motor-driven rack gears for alternate engagement with a rack, a trolley arm carried by the rocker, a trolley rod traversed by a terminal roller of the trolley arm, and terminal stops on the trolley rod for reversing the position of the rocker, said terminal stops being carried by yielding sections of the trolley rod to adapt them to yield as the trolley arm swings from one position to the other in reversal of the rocker.
8. An aircraft having pairs of laterally extended planes or blades mounted for reciprocatory movement in parallel paths longitudinally of the line of flight and in angularly inclined relation to their paths of movement, means for moving the pairs of planes or blades in opposite directions between the limits of their paths of movement, and means for reversing the direction of inclina-

tion of the planes or blades, each plane or blade having a rocking shaft, a toggle having connected arms of which one is carried by said shaft and the other provided with a yieldingly actuated follower, a stop for limiting the movement of said follower, a manually actuated remote control for adjusting

the last said stop, and stops arranged in the path of the toggle at the limits of the path of movement of the plane or blade for reversing the position of said toggle. 10

In testimony whereof he affixes his signature.

HAKON G. LINDQUIST.
